ARTICLE INSPECTION METHOD AND
MACHINE

James B. Whitmore, Bloomfield, William Makenny, Mountain View, and Frank A. Newcombe, Nutley, N. J., assignors to Westinghouse Electric Corporation, East Pittsburgh, Pa., a corporation of Pennsylvania

Application April 21, 1942, Serial No. 439,892

7 Claims. (Cl. 198—33)

This invention relates to article inspection and more particularly to the inspection of lamp bases.

One of the objects of the present invention is to facilitate the inspection of bases for incandescent filament lamps.

Another object is to provide a means operative to automatically feed a plurality of bases for incandescent filament lamps past a point of observation and automatically turn each said base for top and bottom observation.

Still another object is to provide means to feed a succession of lamp bases past a point of observation and to automatically turn each said base so that all parts thereof may be observed.

Other objects and advantages will be apparent as the invention is more fully hereinafter disclosed.

In accordance with these objects, we have devised a lamp base inspection machine, one embodiment of which is shown in the accompanying drawings, wherein:

Fig. 1 is a top plan of the machine;

Fig. 2 is a side elevational view of the same;

Fig. 3 is a fragmentary sectional view on the plane 3—3 of Fig. 1, in the direction of the arrows;

Fig. 4 is an end view partly in section on the plane 4—4 of Fig. 3, in the direction of the arrows;

Fig. 5 is a horizontal sectional view on the plane 5—5 of Fig. 3, in the direction of the arrows;

Fig. 6 is a vertical sectional view on the plane 6—6 of Fig. 3, in the direction of the arrows;

Fig. 7 is a fragmentary enlarged plan, showing a portion of the machine illustrated in Fig. 1;

Fig. 8 is an enlarged fragmentary sectional view on the plane 8—8 of Fig. 7, in the direction of the arrows;

Fig. 9 is a transverse sectional view on the plane 9—9, of Fig. 3, in the direction of the arrows;

Fig. 10 is a partly diagrammatic perspective view of the machine; and

Fig. 11 is a transverse sectional view on the plane 11—11 of Fig. 8, in the direction of the arrows.

Referring to the drawings in detail, and first considering Fig. 10, the lamp base inspection machine of the present invention comprises, in general, a pair of vibrating pans A and B sustained in end spaced relation in a plane inclined at an angle to the horizontal, the upper pan A being provided with a plurality of runways α and means H to feed lamp bases onto the pan

A and distribute the same to the runways, and transfer means C at the bottom of each runway α to convey the bases to pan B and to deposit the same thereon in a position inverted with respect to the position of the same when they leave pan A.

Pans A and B and transfer means C may be mounted for vibration in a plurality of different ways without essential departure from the present invention. In the specific embodiment shown, pans A and B and transfer means C are mounted on a rectangular frame D, in the desired spaced relation, and the latter is supported at the corners by leaf spring members S₁, S₂, S₃ and S₄ projecting diagonally upward from base frame F. The efficiency of the vibratory action for effecting movement of the bases along the pans and transfer means is increased when having the spring members inclined in the same direction as the pans and transfer means, although more steeply, as illustrated, by the variation in the effective weight of said bases. Electrically energized means V is mounted on frame D to vibrate the latter on the springs S₁ to S₄ inclusive, at a frequency effective to impart a relatively rapid rate of movement of the lamp bases along the surface of pans A and B. This frequency may be varied widely without departure from the present invention, with variations in the size of the lamp base and with variations in the rate of travel desired, as one skilled in the art will perceive.

In the inspection of lamp bases of the type shown, the interior and exterior surfaces must be examined for imperfections. Manual inspection of the bases requires the services of a large number of persons and heretofore no machine has been provided which delivers bases in alignment past a point of observation and mechanically performs an inverting operation so that all parts of the bases may be inspected at a desired location. The present invention accomplishes this desired result.

In the specific embodiment shown in Figs. 1 to 9, inclusive, and 11, the lamp bases E are fed from base storage hopper H by means of inclined belt feeder 12 to distributor P which is mounted on frame D to be vibrated with pans A and B and transfer means C. The distributor P desirably carries channel members p to deflect some of the bases E laterally and provide for an even distribution thereof to the pan A. The bottom of the distributor P is formed by a plate 13 overlying the upper portions of runways α

in pan A and supported by member 14 to be vibrated with frame D.

The bases are allowed to fall from the feeder 12 onto distributor plate 13 a sufficient distance so that preferably more than 95% thereof land bottom end down, the bottom end being the heavier end, and are discharged from plate 13 into runways a bottom end down, and thus move down said runways to means C.

Transfer means C comprises a plurality of spiral turn-over chutes, one for each runway a, which bridge the gap between end spaced pans A and B, as shown in Figs. 7, 8, and 11. Preferably, each chute 20 consists of four metal helically curved strips 20. The spacing between opposite strips 20 corresponds with the overall width and height of a base of the kind to be inspected, with only enough clearance to allow free passage of the bases, without allowing them to rotate therebetween. They thus provide a passage, generally square in section, the sides of which are defined by the strips 20, which passage gradually turns, so that there is a reversal or difference of 180° between its ends. The spacing between the strips 20 is sufficient to provide for visual inspection of the sides of the base as it is vibrationally conducted along the chute and inverted in the manner indicated in Fig. 8. Immediately below means C, deflector plates 21 are provided to conduct foreign matter such as glass fragments falling through said means to bin 22, as shown in Fig. 6. Deflector plates 21 are preferably secured to extensions 23 of base frame F.

The electrically energized "Ajax" mechanical vibrator V of the present embodiment of my invention is old in the art. As shown in Fig. 4, it consists of an electric motor 30 mounted on frame F for driving shaft 31 on the end of which is a drive pulley 32 connected by belt 33 to driven pulley 34 of the mechanical vibrator V. The latter is connected to bracket 35 of frame F through cross-bars 36 and 37 to vibrate the same, the period of vibration being determined by the adjustment of rotating weights. The vibrations of the means V are transmitted to frame D and thence to pans A and B, transfer means C, and other parts on frame D.

After the bases E are moved to the end of pan B they are discharged therefrom into laterally converging inclined chutes 40 which deliver them to receptacle 41.

Two inspectors on opposite sides of the device, standing or sitting in front of arm rests 42 and 42', can inspect the bases or other articles when in one position (if bases are inspected, most of them will first be viewed open end up), continuously passing along runways a to transfer means C, and again after reversal of position on pan B, removing defective bases and depositing the same into one of the receptacles 43, 44, 45, 43', 44' or 45'.

The width and length of vibrating pans A and B, the space gap therebetween and length of transfer means C, may be varied without essential departure from the present invention, as may also the means for feeding bases E onto pan A. In general, the length of pan A should be sufficient to provide a bank of bases E ahead of means C and a width providing a plurality of runways within the normal visual range of the two inspectors. The device illustrated provides for the inspection by two girls of from 90,000 to 100,000 bases per hour, as compared to a maximum of 10,000 bases per hour per inspector under the best

arrangement heretofore provided, but including manual handling of the bases.

It is believed apparent that the present invention may be widely varied without essential departure therefrom, and all such modifications and departures are contemplated as may fall within the scope of the appended claims.

We claim:

1. A lamp base inspection device comprising a pair of pans, means supporting the pans in end spaced relation in a plane inclined to the horizontal, the upper one of said pans being provided with a plurality of runways extending in the direction of inclination, and a plurality of helical guides, one for each said runway, bridging the space between said pans to receive bases from the upper pan while reversing their positions and to convey the same to the lower pan, and means to vibrate said pans and guides at a frequency effective to impart a relatively rapid rate of movement to said bases.

2. The combination of claim 1, in which the means supporting the pans comprise a frame on which said pans are mounted in the desired end spaced relation inclined to the horizontal; and the means to vibrate the pans includes the combination of spring means supporting the frame with respect to a base frame, and power means mounted on said supporting frame, the said power means being arranged to impart vibrational impulses causing the bases to travel in the direction of pan inclination.

3. In a lamp base inspection device, an inclined member provided with a plurality of runways extending in the direction of inclination, an inclined plane surfaced member sustained in spaced relation to the first member, a helical guide for each runway bridging the distance between the spaced ends of said members to convey bases traversing the runways to the said second member and deliver the same thereon inverted with respect to the positions on entering the said guides, leaf springs the lower ends of which are fixed and the upper ends of which are supportingly connected to said members and guides, and power means to flex said springs and vibrate the said members and guides thereon in the direction of inclination, thereby to progressively urge bases deposited in said runways through the said guides and onto said second member.

4. An inspection device comprising a support, a plurality of leaf springs secured to and inclined upwardly therefrom; a frame supportedly secured to the upper ends of said springs, vibrator means mounted on said frame, a pair of inclined pans supported on said frame and spaced apart, the upper of said pans being divided by partitions into a plurality of descending runways, a helical guide for each runway for inverting lamp bases, or other articles, received therefrom and transporting them to the lower pan, and a distributor mounted on the upper end portion of said upper pan for receiving bases, or other articles, to be inspected, and properly feeding them to said runways, said distributor, pans, and helical guides being rigid with respect to said frame so as to be vibrated therewith, the pans being inclined in the direction of inclination of said leaf springs, but not as steeply, whereby the vibration of the latter is more effective for moving said bases along said pans and helical guides.

5. An inspection device comprising a support, a plurality of leaf springs secured to and inclined upwardly therefrom, a frame supportedly secured

to the upper ends of said springs, vibrator means mounted on said frame, power means mounted on said support, drive means from said power means to said vibrator means, a pair of inclined pans supported on said frame and spaced apart, the upper of said pans being divided by partitions into a plurality of descending runways and its lower end being above the upper end of said lower pan, a helical guide for each runway for inverting lamp bases, about axes alined with their direction of travel, received therefrom and transporting them to the lower pan, and a distributor mounted on the upper end portion of said upper pan for receiving bases to be inspected, and properly feeding them to said runways, said distributor, pans, and helical guides being rigid with respect to said frame so as to be vibrated therewith, the pans being inclined in the direction of inclination of said leaf springs, whereby the vibration of the latter is more effective for moving said bases along said pans and helical guides.

6. An inspection device comprising a support, a plurality of leaf springs secured thereto, a frame supportedly secured to the upper ends of said springs, vibrator means mounted on said frame, a pair of inclined pans supported on said

frame and longitudinally spaced apart, helical guide means extending longitudinally between said pans for inverting lamp bases or other articles received from the upper pan and transporting them to the lower pan, said pans and helical guides being rigid with respect to said frame so as to be vibrated therewith, and power means for driving said vibrator means.

7. An inspection device comprising a support, 10 a plurality of leaf springs secured thereto, a frame supportedly secured to upper ends of said springs, vibrator means mounted on said frame, a pair of inclined pans supported on said frame and spaced apart, helical guide means connecting the lower end of one pan with the upper end of the other for receiving lamp bases from said first mentioned pan, inverting them, and discharging them into the other pan, said pans and helical guides being rigid with said frame so as to vibrate therewith, and power means for operating said vibrator means to cause the desired movement of said bases through the device.
